UNITED STATES PATENT OFFICE.

WILLIAM E. LEIBING AND LEROY C. TAGGART, OF OAKLAND, CALIFORNIA.

METHOD OF MANUFACTURING EXCELSIOR PADS.

Application filed March 29, 1922. Serial No. 547,755.

To all whom it may concern:

Be it known that we, WILLIAM E. LEIBING and LEROY C. TAGGART, citizens of the United States, residing at Oakland, in the county of Alameda and State of California, have invented certain new and useful Improvements in Methods of Manufacturing Excelsior Pads, of which the following is a specification.

10 The present invention relates to the method of manufacturing pads designed for use in packing articles generally, but more particularly for use in packing furniture, egg crates and the like, where a light weight, durable, cheap packing is required. In packing articles particularly for transportation, it is, in most cases, essential that padding of some sort be employed as a protection against injury or breakage, and due 20 to the voluminous use of packing material, the same must be capable of being purchased at a low cost and clean and easy to handle for the packer. Excelsior and other thin fibre by-products, also moss, have proven 25 to be the cheapest and best materials for general use, but to readily handle the same it has been found essential that the packing material be wrapped in relatively small pads. At present these pads have been manufactured in tubular form with excelsior or like material employed as a filler, but in handling, due to the exposed ends, a packer, in his haste, will grasp the pad and oftentimes spill the contents from the open end of the 35 wrapper. This spilling means considerable mess, entails waste, which is costly, and is undesirable.

Our present method has for its objects to enable the manufacture of a relatively 40 cheap, filled pad adapted to be made and sold at a low cost; one which is sealed, precluding the spilling of the contents thereof when being handled by a packer, and enables its use for packing generally without 45 the muss or mess occasioned by the use of the pads now provided for this purpose.

In carrying out our method we utilize the filled pad forming strip now manufactured and well known on the market, and sever 50 from the same in succession, pad forming sections, and to prevent the spilling of the material from the cut ends thereof we seal the ends as the cut sections are conveyed to a place of deposit.

55 In carrying out our method invention, we have illustrated the essential working in-

strumentalities of an apparatus for performing the steps of the method and the majority of illustrations this apparatus is set forth in substantially diagrammatic form.

In the drawings—

Fig. 1 is a view in plan of one embodiment of an apparatus for carrying out our method invention.

Fig. 2 is a longitudinal sectional view taken on line 2—2 of Fig. 1.

Fig. 3 is a sectional view taken on line 3—3 of Fig. 1.

Fig. 4 is an end view of the filled pad forming strip, illustrating the lap joint of the wrapper.

Fig. 5 is a view in detail of the pad forming strip take-up means and the pad cutting knife, the take-up means being in normal position.

Fig. 6 is a view similar to Fig. 5 illustrating the knife in operation and the take-up means in a position to absorb the continuous feed of the pad material during the cutting operation.

Fig. 7 is a view in side elevation of the end sealing strip curling member and the pivoted end sealing strip compressing member mounted in pairs at opposite sides of the apparatus.

Fig. 8 is a sectional view taken on line 8—8 of Fig. 7, with the pivoted end sealing strip compressing member in raised position.

Fig. 9 is a view similar to Fig. 8 with said member in lowered position.

Fig. 10 is a view in perspective of one of the pads, illustrating the manner of applying the end sealing strips thereto.

Fig. 11 is a view in perspective of the finished pad.

In carrying out our method invention, the apparatus illustrated, particular reference being had to Figs. 1 and 3, comprises endless conveying belts 1 and 2 operating around rollers 3 and 4 in slight parallel spaced relation and between opposite faces of said belts the filled pad forming strip 5 is conveyed in a continuous length, the strip containing a filler 6, Fig. 4, of excelsior, moss or like long fibre material, which is enclosed by a wrapper 7, lapped as at 8, forming a longitudinal seam.

From the ends of the belts 1 and 2, and due to their action, the continuous filled strip of pad forming material is conveyed

between the parallel flights 9 of the guide and restoring belts 10, the flights 9 operating around end rollers 10' and the respective drive rollers 11, which are operated in any suitable manner to move the belts in the direction of the arrows—Fig. 3.

Associated with each belt is a pivotally mounted, spring hold, take-up roller 12 carried by an arm 13—Fig. 3 of the drawings.

On the inner side of each belt flight 9, extending transversely across the belt, is a roller 13', the rollers being connected at their ends by a frame 14 which is fulcrumed on a horizontal axis 15, and from said frame extends an arm 16 connected through a link 17 with one end of a lever 18, pivoted as at 19, and carrying a cam surface 20. The cam surface 20 is acted on by opposing cams 21 carried by the shaft 22 supporting the roller 4, and between the end of the lever 18 and the end of link 17 there is afforded a limited amount of play as illustrated in Fig. 3.

At one end of the passageway formed by the belt flights 9, the conveyed pad forming strip passes over a support 21 disposed transversely beneath the same and above said support is mounted for vertical reciprocation a presser foot 22', the stem 23 of which passes through spaced guides carried by a block 24, the foot being yieldably mounted by a spring 25. At the inner edge of the support 21 is positioned a cutting blade 26 and with the same cooperates a cutting blade 27 carried by the block 24. A cam 28 on a shaft 29, which is operated in timed relation with the shaft 22, operates the block 24 to depress the foot 22, operate the knife 27 and sever a pad from the strip 5.

At the time of the operation of the foot 22' and the arresting of the movement of the strip 5, the rollers 13, through the lever 18 and link 17, are moved from their position in Fig. 5 to that in Fig. 6, taking up the continuous feed of strip 5 until such time as the foot 22 is released. On the release of the foot 22 the belt take-up rollers 12 restore a previously bent portion of the strip 5 to a horizontal position and project the end thereof beyond the knives 26 and 27.

The previously described mechanism sets forth one embodiment of an invention for carrying out our method invention, whereby independent pads are formed from a strip of filled pad forming material.

The pads as formed by severing the projecting end of the strip 5 transversely by the action of the cutting knives 26 and 27, fall on a reciprocating pad receiving table 30, operating over a support 31, and reciprocates in timed relation with the operation of the cam 28 by any suitable mechanism.

The blade 26 forms one side edge of the table and a flange 32 forms the opposite side

edge of the table. The table at its front edge is unobstructed and at its rear carries a pad engaging lip 33. Transversely across the end of said table 30, one above and one below the same, are the conveying rollers 34, and around said rollers pass the pad compressing and feed belts 35, which also operate around rollers 36, which divide the belt into upper and lower flights disposed in parallel relation, the upper flight of the lower belt operating over a compressing table or support 37, and the lower flight of the upper belt being disposed in parallel relation therewith, and said upper belt being provided with a take-up 37'. 80

The pad end sealing strips are mounted preferably in roll form as at 38 and the respective strips as unwound from the rolls pass around suitable idlers 39 which direct the same around other idlers 40 disposed above adhesive supplying means 41 dipping into a tank 42, thus on the feed of the strips from the rolls 38, one surface thereof is supplied with an adhesive of any suitable type. The strips after receiving the adhesive 90 pass in a horizontal direction beneath the support 31 and in parallel relation between rotating cutting rollers 43 operated in any suitable manner and extending preferably transversely beneath the support 31. Associated with the cutting rollers 43 are the strip section feed rollers 44 for picking up the section after it is cut from the strip and for feeding the same upwardly on the incline 45 disposed parallel with the lower 100 roll 34 and delivering the same at a point beneath the severed pad as the same is advanced by the lip 33. The rolls 43 and 44 are operated in timed relation and it will be observed that after a section of sealing strip 105 is cut from the main body of the strip forming material that the continued rotation of the cutting rolls picks up the end of the strip and feeds the same to the feed rolls 44, and that the cut section is engaged by 110 the rolls 44 before the same is severed from the main body of sealing strip forming material. The upper roll 34 has one or more pad engaging teeth 46 adapted on each revolution to engage the pad as moved forwardly on the table 30 and to advance the same between the belts 35 and simultaneously with the engagement of the teeth 46 with the pad, the action of the belts 35 compresses the forward edge of the pad onto the forward end 115 of the severed end sealing strips, which have been fed beneath the same by the rolls 44.

The action of the belts 35 is to propel the pad, with the end sealing strips adhesively engaging the under face of the ends thereof, over the table or support. During this conveying, a portion of each end sealing strip projects, as at 47, beyond the end of the pad, and to curl the same thereover and close the opposite open ends of the pads 120

we provide at each side of the lower belt 35, inwardly converging upwardly and inwardly curled end sealing strip curling members 48, which extend parallel with the lower belt 35 to a point slightly beyond the take-up 37, as in Fig. 1, and the conveying of the pad beyond said members causes the members to raise the projecting portion of the end sealing strips to a substantially vertical plane. Beyond said members 48 we position one on each side of the lower belt 35, the pivotally mounted end sealing strip folding and compressing members 49, pivoted as at 50, and which are operated in timed relation to swing on said pivot from the position indicated in Fig. 8 to that in Fig. 9.

It will be observed that the members 49 raise the projecting ends 47 of the sealing strips from a horizontal to a vertical position, and that the action of the members 49 folds the upwardly extended edge downwardly over the ends of said pads, forming an end seal, as indicated in Fig. 11, with each end of the pad closed by a substantially U-shaped end closure member 51 adhesively secured thereto.

Having thus described our invention what we claim as new and desire to secure by Letters Patent of the United States is:—

1. A method of making sealed packing pads, consisting in continuously feeding a strip of wrapped packing material into a machine, stopping the movement of said strip at predetermined intervals therein, severing the end portion from said strip to form a pad section while it is stopped, feeding the successively severed sections through the machine in spaced relation and feeding and applying adhesively coated strips over the cut ends of said pad sections to close said ends and complete the pad, and delivering said completed pads from the machine.

2. A method of making sealed packing pads, consisting in continuously feeding a strip of wrapped packing material into a machine, intermittently stopping and severing the end portion from the strip to successively form a series of pad sections, feed-

ing said sections through the machine in spaced relation, feeding a pair of paper strips into said machine, gumming and severing strip sections from the said paper strips, successively feeding said strip sections into engagement with said pad sections, folding said strip sections over the open ends of said pad sections for sealing said ends to form a closed sealed pad and delivering said sealed pads from the machine.

3. A method of making sealed packing pads, consisting in continuously forming a series of pad sections from a wrapped packing strip, feeding said sections in spaced relation through a machine, forming opposed gummed strip sections from paper strips, feeding said strip sections in parallel spaced relation into engagement with the pad sections and applying said strip sections over the open ends of said pad sections to seal said pad sections, and successively delivering said sealed packing pads from the machine.

4. A method of making sealed packing pads, consisting in continuously feeding a strip of wrapped packing material into a machine, intermittently stopping and severing the end portion from the strip to successively form a series of pad sections, providing a take-up for said strip during and adjacent the point of stopping thereof for holding and guiding the movement of the strip, feeding said sections through the machine in spaced relation, feeding a pair of paper strips into said machine, gumming and severing strip sections from said paper strips, successively feeding said strip sections into engagement with said pad sections, folding said strip sections over the open ends of said pad sections for sealing said ends to form a closed sealed pad and delivering said sealed pads from the machine.

In testimony whereof we have signed our names to this specification.

WILLIAM E. LEIBING.
LEROY C. TAGGART.
